(57) **CLAIM**

The ornamental design for a sensor module for a road paver, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 shows a view onto the front side of a sensor module for a road paver showing my new design;

FIG. 2 shows a view onto the left side of the sensor module for a road paver of FIG. 1;

FIG. 3 shows a view onto the rear side of the sensor module for a road paver of FIG. 1;

FIG. 4 shows a view onto the right side of the sensor module for a road paver of FIG. 1;

FIG. 5 shows a view onto the top side of the sensor module for a road paver of FIG. 1;

FIG. 6 shows a view onto the bottom side of the sensor module for a road paver of FIG. 1;

FIG. 7 shows a perspective view onto the front side, right side and top side of the sensor module for a road paver of FIG. 1; and,

FIG. 8 shows a further perspective view onto the front side, left side and bottom side of the sensor module for a road paver of FIG. 1.
